US00D924485S

(12) **United States Design Patent** (10) Patent No.: **US D924,485 S**
(45) Date of Patent: **** Jul. 6, 2021**

(54) **HAIR REMOVAL DEVICE**

(71) Applicant: **Happy Skin Co Pty Ltd**, Prestons (AU)

(72) Inventor: **Francesco Costacurta**, Sacile (IT)

(73) Assignee: **Happy Skin Co Pty Ltd**, Prestons (AU)

(**) Term: **15 Years**

(21) Appl. No.: **29/706,505**

(22) Filed: **Sep. 20, 2019**

(30) **Foreign Application Priority Data**

Jul. 22, 2019 (AU) 201914095

(51) **LOC (13) Cl.** **28-03**

(52) **U.S. Cl.**

USPC **D28/44.1; D24/209**

(58) **Field of Classification Search**

USPC D28/44.1; D24/200, 209, 214
CPC A61B 18/203; A61B 18/00; A45D 26/00;

A45D 2200/205; A45D 2200/15-157
